US00D748606S

(12) **United States Design Patent**
Abayomi et al.

(10) **Patent No.:** US D748,606 S
(45) **Date of Patent:** ** Feb. 2, 2016

(54) **SPEAKER STAND**

- (71) Applicant: **Apple Inc.**, Cupertino, CA (US)
- (72) Inventors: **Remi Abayomi**, London (GB); **Jonathan Tatkon-Coker**, Santa Monica, CA (US); **Rodrigo Sobral Franca**, London (GB); **Jeff Gormley**, Los Angeles, CA (US); **Judy Kuo**, Santa Monica, CA (US); **Freddy Martinez**, Canyon Country, CA (US); **Alex Wills**, London (GB); **James Temple**, Hitchin (GB); **Peter Jupp**, Leigh on Sea (GB)
- (73) Assignee: **Apple Inc.**, Cupertino, CA (US)
- (**) Term: **14 Years**
- (21) Appl. No.: **29/510,331**
- (22) Filed: **Nov. 26, 2014**

Related U.S. Application Data

- (63) Continuation of application No. 29/472,814, filed on Nov. 15, 2013, now Pat. No. Des. 729,213.
- (51) **LOC (10) Cl.** 14-01
- (52) **U.S. Cl.** USPC D14/215; D14/224.1
- (58) **Field of Classification Search**

(57) **CLAIM**

The ornamental design for a speaker stand, as shown and described.

DESCRIPTION

FIG. 1 is a front perspective view of a speaker stand in accordance with the present invention;

FIG. 2 is a front view of a speaker stand in accordance with the present invention;

FIG. 3 is a top view of a speaker stand in accordance with the present invention;

FIG. 4 is a left side view of a speaker stand in accordance with the present invention, the right side view being a mirror image thereof;

FIG. 5 is a rear view of a speaker stand in accordance with the present invention; and,

FIG. 6 is a bottom view of speaker stand in accordance with the present invention.

The broken lines showing the environment in the Figures are for illustrative purposes only and form no part of the claimed design.

1 Claim, 2 Drawing Sheets
